UNITED STATES PATENT OFFICE

1,980,924

ROTARY GAS ENGINE

Charles G. McDonald, St. Marys, Mo.

Application September 9, 1931, Serial No. 561,940

1 Claim. (Cl. 123—44)

This invention relates to rotary internal combustion engines wherein the cylinders are adapted to rotate about a fixed crank shaft with the pistons thereof connected to said crank shaft and 5 has for the primary object, the provision of the cylinders and pistons arranged in opposed relation and so constructed that they cooperate in providing an engine of the two-cycle type and which will be simple, durable, compact and 10 economical in operation and capable of producing maximum power with a minimum consumption of fuel.

With this and other objects in view, this invention consists in certain novel features of construction, combination and arrangement of parts to be hereinafter more fully described and claimed.

For a complete understanding of my invention, reference is to be had to the following description and accompanying drawings, in which 20 Figure 1 is a side elevation illustrating an internal combustion engine constructed in accordance with my invention.

Figure 2 is a sectional view taken on the line 2—2 of Figure 1.

Figure 3 is a sectional view taken on the line 3—3 of Figure 2.

Figure 4 is a sectional view taken on the line 4—4 of Figure 1.

Referring in detail to the drawings, the numeral 30 1 indicates a supporting structure having bearings or journals 2 for rotatably supporting trunnions 3 secured to opposed cylinders 4 and 5. The trunnions 3 carry bearings 6 in which are received a non-rotatable crank shaft 7 and which is fixed 35 to the supporting structure 1 by a key or pin 8. The adjacent ends of the cylinders 4 and 5 form a crank case 9 in which is located the crank 10 of the crank shaft 7 and said crank shaft is provided with a passage 11 communicating with 40 the crank case 9 by a port 12 and with an intake manifold 13 adapted for connection with a suitable carburetor.

Pistons 14 and 15 are mounted within the cylinders 4 and 5 and a connecting rod 16 is connected to the piston 15 and is provided with a detachable bearing 17 connecting the crank 10 of the crank shaft and has pivoted thereto a connecting rod 18 which is in turn connected to the piston 14.

50 The cylinders 4 and 5 have explosion chambers 19 and 20 and also fuel compression chambers 21 and 22, respectively. By referring to Figure 2 it will be noted that the fuel compression chambers 21 and 22 are of a diameter larger than the diameter of the explosion chambers 19 and 20 and the

pistons 14 and 15 each includes a body 23 with an annular head 24 formed on one end. The heads 24 operate in the fuel compression chambers while the bodies 23 operate in the explosion chambers and also extend into the fuel compression chambers during certain positions of the pistons relative to the cylinders. The bodies and heads 23 and 24 of the pistons are provided with expansion rings as clearly shown in Figure 2.

The explosion chambers 19 and 20 are provided 65 with exhaust passages 25 opening outwardly to the atmosphere and said passages are located in the cylinders outwardly of the compression chambers 21 and 22. Intake passages 26 and 27 are formed in the walls of the cylinders 4 and 5 and 70 each has one end in communication with a fuel compression chamber while the opposite end is in communication with an explosion chamber so that fuel compressed within the compression chamber will be delivered to the explosion chamber located 75 in the opposite cylinder to said compression chamber. Intake valves 28 and 29 are located in the passages 26 and 27 and have communication with the crank case 9 and each is of the spring pressed type adapted to be opened by the suction created 80 within the compression chambers and adapted to move into setting position when the suction is eliminated and when in the latter named position are adapted to permit free passage of fuel through the passages 27 and 26 from 85 their respective compression chambers to the explosion chambers. The explosion chambers are provided with spark plugs 30 and the end of each piston is provided with a deflector 31 for the purpose of deflecting the incoming fuel to the explosion chambers upwardly within said chambers for the purpose of driving out or scavenging the burnt gases of said chambers.

The cylinders are provided with relatively spaced annular fins or flanges 32 for aiding in 95 cooling the cylinders during their rotation about the fixed crank shaft consequently providing a very efficient means of maintaining the engine in a properly cooled or normal running condition and obviates the employment of water jackets and 100 circulating pumps and other parts of the conventional type of cooling system.

One of the trunnions 3 has secured thereto a power take off medium 33.

As shown in Figure 2 the piston 14 is in its 105 outermost position within the cylinder 4 while the piston 15 is in its innermost position within the cylinder 5. The piston 14 positioned as above mentioned has compressed a charge of fuel and is in the act of exploding the same for driving 110

the piston 14 inwardly. The piston 14 when in the stated position has forced the fuel within the chamber 21 into the explosion chamber 20 and the piston 15 has drawn fuel into the chamber 22 from the carburetor by way of the manifold 13, passage 11, port 12, crank case 9 and the fuel passage 27. As the piston 14 moves inwardly under the force of the expanding gases which have just been ignited moves the piston 15 in an outward direction within the cylinder 5 compressing the fuel within the explosion chamber 20. The piston 15 moving outwardly forces the fuel within the chamber 22 into the explosion chamber 19 while the piston 14 has by this time uncovered the intake passage and opened the exhaust passage of the cylinder 4. The incoming fuel forces the burnt gases outwardly through the exhaust passage, the deflector 31 directing the incoming fuel toward the closed end of the explosion chamber and in that way aid in forcing the burnt gases from the explosion chamber, thus it will be seen that a two-cycle engine has been provided wherein the cylinders and pistons are oppositely disposed and rotate about a fixed crank shaft thus providing an engine capable of producing maximum power with a minimum consumption of fuel and also due to the rotation of the cylinder provides a very efficient cooling medium for the engine.

30 While I have shown and described the preferred

embodiment of my invention, it will be understood that minor changes in construction, combination and arrangement of parts may be made without departing from the spirit and scope of my invention, as claimed.

Having thus described my invention, what I claim is:—

A rotary engine comprising a supporting structure, a single cylinder journaled intermediate its ends to said structure and having two diameters, opposed pistons slideable in said cylinder and each having a pair of diameters corresponding to the diameters of the cylinder and forming in the latter pairs of explosion and compression chambers separated by said pistons, and an intermediate fuel chamber located between the opposing ends of the pistons, a crank shaft journaled to the cylinder and fixed to said supporting structure and having a passage to admit fuel to said fuel chamber, means connecting the crank shaft to said pistons, said explosion chambers having exhaust ports, said cylinder having in opposite walls thereof intake fuel passages connecting the explosion chambers with the compression chambers arranged at opposite sides of the intermediate fuel chamber from the respective explosion chambers, self-seating valves between the intake fuel passages and the intermediate fuel chamber, and ignition means for the explosion chambers.
